UNITED STATES PATENT OFFICE.

MARTIN L. ANDREWS, OF TROWBRIDGE, PENNSYLVANIA.

CLOTHES-RACK.

1,109,275.

Specification of Letters Patent. Patented Sept. 1, 1914.

Application filed September 17, 1913. Serial No. 790,279.

To all whom it may concern:

Be it known that I, MARTIN L. ANDREWS, a citizen of the United States of America, and resident of Trowbridge, county of 5 Tioga, State of Pennsylvania, have invented certain new and useful Improvements in Clothes-Racks, of which the following is a specification.

This invention relates to clothes racks and 10 more particularly to a form of rack of the lazy tongs type arranged so that the rack may be collapsed into a small space when not in use and when in use may be drawn out and present a series of supporting bars 15 for clothes and the like.

The principal object of the invention is to provide a rack which may be hung on a vertical wall in closed and open position and may also be removed from the wall, 20 opened and supported in an arched position on the floor.

A further object is to so construct the rack that it will form a series of horizontal shelves adjacent the wall when hung on the 25 wall in closed position and may also be drawn from this position into a substantially horizontal clothes rack supported only from the wall.

The above and other objects and the novel 30 features of the invention will be apparent from the following description, taken in connection with the drawing, in which—

Figure 1 is a perspective view of the rack hung from the wall and in open position; 35 Fig. 2 is a perspective view of the same in closed position; and Fig. 3 is a side elevation of the rack inverted and supported in an arched position on the floor.

The rack comprises a pair of parallel 40 lazy-tongs connected together by means of a series of parallel cross-bars. Each lazy-tongs comprises a series of pairs of substantially similar cross-levers or slats 10, 101 pivoted together intermediate their ends as 45 at 11. Each pair of levers has its ends pivotally connected to an adjoining pair of levers as indicated at 12 and 13. The parts of the rack are made of wood or any other suitable material and the pivotal connections for the levers 10, 101, are formed by the reduced ends of the parallel cross-bars 50 14, the said reduced ends extending through registering holes in the ends of the levers 10, 101, and for some distance beyond the outer side thereof to form hooks as at 55 15 for articles of clothing and the like.

The intermediate pivotal connection 11 of each pair of levers is slightly to one side of the longitudinal center of the levers pivoted together by said connection so that the rack 60 will form an arch as indicated in Fig. 3 when inverted and set on a horizontal support F.

A long lever 16 and a short lever 17 are pivotally connected to each lazy-tongs at 65 one of its ends, the end of the short lever 17 being pivotally connected to the lever 16 beyond the center of the latter, slightly closer to the free end thereof. A long lever 18 and a short lever 19 are pivotally 70 connected at their ends to each of the other ends of the lazy-tongs, the end of the short lever 19 being pivotally connected to the long lever 18 intermediate the ends thereof and slightly nearer the attached end of lever 18. The levers 17 and 19 are therefore 75 of unequal lengths and do not touch the floor F when the rack is set up as shown in Fig. 3. It will be noticed furthermore that the levers 17, 17 are disposed on the 80 inside of the arch while the levers 19, 19 are on the outside of the arch formed by the rack. In order to brace the free ends of levers 16, 16 and 18, 18, they are rigidly connected together by the cross-bars 20 and 21 85 respectively, the said free ends serving as supporting feet for the rack when it is supported as shown in Fig. 3. The cross-bar 20 extends a somewhat greater distance beyond the outer faces of the levers 16 to form 90 engaging means on the rack for the hooks 22, 22, the latter being secured to the vertical wall W and constituting supporting means on said wall for the rack. The hooks 22, 22 at opposite ends of the cross-bar 20 95 serve to support the rack in either open or closed position, the rack being braced against the wall by the frame formed by the levers 16, 16, cross-bars 14, 14 and 20. Levers 17, 17, connected near the center of the 100 frame and levers 10, 10 attached at the bottom serve to support the rack from the wall. When the rack is drawn to an open position it will assume a downwardly curved shape as shown in Fig. 1, the arrangement of the 105 levers of the lazy-tongs serving to transmit the strain and support the rack from its attached end.

The lazy tongs are made up of a series of pivotally connected pairs of levers, the 110 levers constituting each pair being pivoted together beyond the longitudinal centers

thereof so that the arms of each of the pairs of levers will be of unequal length, causing the rack when extended to assume a curved or arched position, the shorter arms being 5 on the inside of the arch formed when the rack is extended from the wall or rests on the floor. When extended from its support on a vertical wall, the rack will swing downwardly on a curve, and, accordingly hangs 10 in a more stable condition than if it extended at substantially right angles to the wall. To collapse the rack from the extended or curved position when hanging from a wall, it must be pushed upwardly as well as inwardly toward the wall. When the rack is set up on a horizontal support or when it is drawn out from a collapsed position when it hangs on a wall, the cross bars 14 thereof will be so disposed as to be vertically out 15 of line, and thus provide more bar length for hanging up clothes and the like.

The end frame formed by the levers 16, 16, cross-bar 18, and cross-bars 14, 14, parallel thereto, is so formed and the remaining 25 parts of the device are so attached thereto that when the said frame is hung on the wall as shown in Fig. 1 the rack will be disposed in substantially a horizontal position. Racks of the ordinary construction are not 30 adapted to be attached to a wall and still admit of the removal of the same from the wall and the adjustment in an arched position on a horizontal support.

Referring to Fig. 2 it will be seen that 35 when the rack is folded the cross-bars thereof fit alongside one another and form a set of horizontal shelves 23 adjacent the wall W so that the device also has a function when it is closed and not in use as a rack. The 40 projections or hooks 15 are then also serviceable to hang articles on. The number of horizontal bars 14 forming each shelf is the same, making the shelves of equal width.

The levers 10, 101 close the shelves at their ends.

The rack may be of more or less members but it is necessary that it always have the same arrangement of parts. The ratio between the short and long distance between the bars forming pivots for the levers may 50 be changed slightly, however it is necessary to observe the proportions in order to obtain a satisfactory device. Other minor modifications may be made without departing from the spirit of the invention and therefore I do not wish to be limited to the exact details as shown and described.

Having thus described the invention, what is claimed is:

In a clothes rack, the combination of a 60 pair of lazy tongs each comprising a series of pivotally connected pairs of similar levers, cross bars joining said lazy tongs and forming a frame with the levers at one end, the levers adjacent to the end being permanently connected to said frame, the ends of 65 said cross bars constituting the pivotal connections for the levers forming the lazy tongs, the levers comprising each pair of levers being pivoted together beyond their 70 longitudinal centers so as to form arms of unequal length of each of the levers constituting a pair whereby said rack, when extended, will extend along a curve and form an arch-like support for clothes, said frame 75 being adapted to be attached to a wall and support the rack so that it will hang downwardly and outwardly on a curve from said wall.

In testimony whereof I affix my signature 80 in presence of two witnesses.

MARTIN L. ANDREWS.
